FAN HOOD

Hercheal Wood Miller, Davenport, Iowa, assignor to American Machine and Metals, Inc., East Moline, Ill., a corporation of Delaware

Application April 19, 1956, Serial No. 41,127

Term of patent 14 years

(Cl. D62—3)

Fig. 1 is a perspective view of a fan hood embodying my new design;

Fig. 2 is a reduced side view thereof; and

Fig. 3 is a bottom plan view thereof with portions broken away for convenience of illustration.

What is claimed is:

The ornamental design for a fan hood, substantially as shown.
